US00D816218S

(12) **United States Design Patent** (10) **Patent No.:** **US D816,218 S**
(45) **Date of Patent:** **** Apr. 24, 2018**

(54) **ANTERIOR OCULAR SEGMENT
OBSERVATION DEVICE**

(71) Applicant: **KOWA COMPANY, LTD.**,
Nagoya-shi, Aichi-ken (JP)

(72) Inventors: **Naoki Kambe**, Kawasaki (JP); **Nozomu
Toriba**, Tokyo (JP)

(73) Assignee: **KOWA COMPANY, LTD.**,
Nagoya-Shi, Aichi-Ken (JP)

(**) Term: **14 Years**

(21) Appl. No.: **29/525,243**

(22) Filed: **Apr. 28, 2015**

(30) **Foreign Application Priority Data**

Oct. 30, 2014 (JP) 2014-024232

(51) **LOC (11) Cl.** **24-00**

(52) **U.S. Cl.**
USPC **D24/137**

(58) **Field of Classification Search**

(57) **CLAIM**

The ornamental design for an anterior ocular segment observation device, as shown and described.

DESCRIPTION

FIG. 1 is a front view of the anterior ocular segment observation device, according to our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front perspective view thereof; and,

FIG. 8 is a rear perspective view thereof.

In the drawings, the broken lines are for the purpose of illustrating environment only and form no part of the claimed design.

1 Claim, 8 Drawing Sheets
